BOTTLE CAP

Application filed February 28, 1930. Serial No. 431,363.

The invention relates to closure caps for bottles and analogous containers, and its object is to provide an improved cap of spring sheet metal including peripheral locking fingers having overlapping engaging portions which increase the resilient gripping action, and also to so form the fingers and their overlapping portions as to provide a generally smooth peripheral surface or contour.

The characteristics and advantages of the invention are further sufficiently explained in connection with the following detail description of the accompanying drawing, which show representative embodiments. After considering these examples, skilled persons will understand that many variations may be made without departing from the principles disclosed, and I contemplate the employment of any structures that are properly within the scope of the appended claims.

In the drawing:

Fig. 1 is a plan view of a blank for the production of the cap in one form embodying the invention.

Fig. 2 is an edge view.

Fig. 3 is a view, partly in elevation and partly in section, of the completed cap produced from the blank of Figs. 1 and 2, in position for application to a bottle neck.

Fig. 4 is a similar view showing the cap in applied or sealing position.

Fig. 5 is a section at 5—5 of Fig. 3.

Fig. 6 is an edge view of a modified structure.

Fig. 7 is a section at 7—7 of Fig. 6.

Fig. 8 is an enlarged fragmentary section similar to Fig. 5 explaining a tapered or swaged overlapping formation of finger members.

The invention provides improvements in closure caps of the character disclosed in patent to Henry Spengler, No. 1,589,575, in which alternate locking fingers have alternate over-and under-lapping marginal portions by which the over-lapping members reinforce or amplify the resilient gripping action of the other fingers. In the patented structures, however, the overlapping finger portions are of normal or unreduced thickness and produce a cap contour which is undesirably ir-

regular, including abrupt shoulders formed by the edges of the overlapping members. This is objectionable for various reasons, including liability of the irregular peripheral surfaces, or thick exposed edges of the fingers, to injure hands of the user, irregular appearance of the cap, and other reasons as understood by skilled persons.

An important feature of the present invention consists in so forming by bending, pressing, swaging, or otherwise, the overlapping and co-operating finger portions, that the peripheral contour of the cap is substantially smooth and uniform, without abrupt shoulders or thick overlapping edges, thus imparting to the cap a neat and trim appearance, preventing injury to fingers of the user, and at the same time providing the desired firm locking effect by mutual action of the overlapping finger portions.

In the form shown in Figs. 3 and 4, the cap 1 is produced from a blank 2, Figs. 1 and 2. This blank is a circular disc of spring sheet metal 1, usually steel. In the margin of the disc are cut uniformly spaced approximately radial but actually non-radial or angular slits 3, the angularity of all of the slits being similar or symmetrical with respect to the circular form of the blank. The peripheral portion of the blank is thus separated into locking fingers 4. One edge of each finger is pressed to form a substantially triangular segment 5 which as best shown in Fig. 2, is depressed from the general plane of the disc, and at the same time the main finger portions 4 may be bent slightly at angles to the disc plane.

The blank is then pressed to the form shown in Fig. 3, including a central or body portion 6 of moderately convex form, terminating peripherally in a shallow channel which produces an internal convex bead 7 to overlie the bottle rim, and the locking fingers are bent curvedly or convexly downward, with the plain or undepressed margin 8 of each finger overlying the depressed triangular portion 5 of the next adjacent finger, the edge of each finger margin 8 confronting the shouldered portion 5a of the adjacent finger where the depressed or triangular portion 5 joins the 10a

main portion 4 of its finger. Thus, as clearly shown in Fig. 3, the external contour of the locking portion is practically smooth, without any projecting shoulders or edges.

5 A gasket or packing disc 9 of suitable material is usually provided, placed within the cap, and when the cap is snapped into position on the beaded rim 10 of a bottle neck 11, Fig. 4, a marginal portion of the packing disc is compressed between annular shoulder 7 and the bottle rim to form a hermetic seal. In the applying action the fingers of course spring outward, and finally their lower portions engage under the neck bead 10, the resilient gripping action of each finger being reenforced and amplified by the overlapping engagement with it of the next adjacent finger. The cap is thus secure against accidental removal or leakage but is readily removed by any ordinary finger pressure.

20 Fig. 5 shows in section the overlapping relation of the finger portions, and Fig. 8 shows that the finger margins 8^a which overlie the depressed or inbent marginal portions 5 of the adjacent fingers may be pressed or swaged to reduce the thickness of said finger portions 8^a and prevent any projection of their edges beyond the general contour of the periphery of the finger structure.

25 Figs. 6 and 7 show a modification in which each finger 4 has at one side, in a mid-length position, a rounded projecting portion or lug 15 which interfits with and overlaps an impressed segment 16 of the adjacent finger.

30 The overlapping portions 15 and 16, or either of them, may be pressed or swaged to reduce their thickness and produce practically a perfectly smooth, uniform peripheral contour as clearly shown in Fig. 7.

40 I claim:

1. A closure cap of sheet metal comprising a body portion and down-bent locking fingers, similar edges of the fingers being inbent and other similar edges of the fingers overlapping the inbent portions, producing a substantially smooth and uniform peripheral finger surface contour.

45 2. A closure cap of sheet metal comprising a body portion and down-bent locking fingers, similar edges of the fingers being inbent and other similar edges of the fingers overlapping the inbent portions, producing a substantially smooth and uniform peripheral finger surface contour, and the overlapping finger portions mutually increasing the resilient engagement of the fingers with a container neck formation.

50 3. A closure cap of sheet metal comprising a body portion and down-bent locking fingers, similar edges of the fingers being inbent and other similar edges of the fingers overlapping the inbent portions, producing a substantially smooth and uniform peripheral finger surface contour, the body portion hav-

55 ing near the points of juncture with the fingers an annular impressed bead to co-operate with a packing disc.

4. A closure cap of sheet metal comprising a body portion and down-bent locking fingers, similar edges of the fingers being inbent and other similar edges of the fingers overlapping the inbent portions, producing a substantially smooth and uniform peripheral finger surface contour, the body portion having near the points of juncture with the fingers an annular impressed bead, and a packing disc within the cap, the annular cap bead co-operating with the margin of the disc to form a seal when the cap is applied to a container neck.

5. A closure cap of sheet metal comprising a body portion and down-bent locking fingers, each finger having an impressed triangular margin with a shoulder between it and the main finger portion, the other margins of the fingers overlying the impressed triangular portions, with their edges confronting the shoulder formations, providing a smooth exterior finger contour.

6. A bottle cap of spring sheet metal including a body portion and separate locking fingers extending curvedly downward therefrom, each finger having at one side a depressed formation and each finger having at its other side a rounded projection, the projections fitting in the depressions to augment resilient finger action and provide a smooth peripheral cap contour.

7. In testimony whereof I affix my signature.

HENRY SPENGLER.
